(57) CLAIM

The ornamental design for packaging container with surface ornamentation, as shown and described.

DESCRIPTION

FIG. 1 is a perspective view of packaging container with surface ornamentation embodying our new design;

FIG. 2 is a front view thereof;

FIG. 3 is a back view thereof;

FIG. 4 is a top view thereof;

FIG. 5 is a bottom view thereof;

FIG. 6 is a left view thereof; and,

FIG. 7 is a right side view thereof.
